CLAIM

The ornamental design for a display screen with icon, as shown and described.

DESCRIPTION

FIG. 1 is a front view of a display screen with icon, showing the new design; and,

FIG. 2 is a front view thereof, shown in the environment of an electronic device.

The broken lines of even length illustrate an electronic device with display screen and portions of a graphical user interface. The broken lines of uneven length define the bounds of the claim, and, in FIG. 1, illustrate a display screen. The broken lines form no part of the claimed design.
